UNITED STATES PATENT OFFICE.

BRADLEY A. FISKE, OF NEWPORT, RHODE ISLAND, ASSIGNOR TO BERNARD HECHT, OF NEW YORK, N. Y.

PENCIL OR CRAYON HOLDER.

SPECIFICATION forming part of Letters Patent No. 272,948, dated February 27, 1883.

Application filed July 6, 1882. (No model.)

To all whom it may concern:

Be it known that I, BRADLEY A. FISKE, a citizen of the United States, residing at Newport, in the county of Newport and State of Rhode Island, have invented certain new and useful Improvements in Pencil or Crayon Holders; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to an improvement in lead-pencils having sliding leads, its object being to provide for readily projecting and retracting the lead; and it consists in a longitudinally-apertured sheath, which is inserted 20 at its inner end in a cylinder, with said end resting against an apertured stop, while the lead, at its inner end, is held by a tube passed through the apertured diaphragm or stop, said lead, if it is desired to dispense with the tube, 25 being passed through and headed on the rear side of the diaphragm, a rubber plug or eraser, which may be used or not, being inserted in the rear end of the cylinder, substantially as hereinafter more fully set forth.

30 In the accompanying drawings, Figure 1 is a side view of my pencil. Fig. 2 is a longitudinal section, and Figs. 3 and 4 are detailed views, in perspective, of the same. Fig. 5 is a sectional view of a modification of the same.

35 In carrying out my invention I employ a longitudinally apertured sheath, A, whose aperture contains the lead a. The sheath, which is preferably made of wood, is tapered or pointed during the sharpening of the lead, or 40 is cut away as the lead wears down.

B is a slotted cylinder, into which the sheath A is inserted a suitable depth or distance, and which clasps or clamps the latter.

45 C is a tube held centrally in the cylinder B by an apertured stop or block, b, wedged or

forced into the rear end of the cylinder a suitable distance therefrom, said tube passing through the block or stop b. In the rear of this block the cylinder B may be fitted with a rubber plug or eraser, D. The tube is adapted 50 to clamp and thus hold the lead at its inner end. The block or stop b is adapted to limit the insertion of the sheath into the cylinder.

It will be observed that after the sheath A has been cut away to prepare the pencil for 55 use the lead will project beyond the sheath, in which position, if pressed upon a table or other surface, it will push the cylinder B outwardly, leaving a space between the stop b and the inner end of sheath A equal in distance 60 to the length which the writing end of the lead projected from the sheath. Having thus retracted the lead, it is only necessary, in order to project it for use, to press the butt-end of the pencil on the table or other surface. 65

In Fig. 5 I have dispensed with the tube and substituted for the apertured block an apertured diaphragm or disk, through which I pass the lead and provide it with a shoulder on the rear side of said disk to prevent the falling 70 out of the lead.

I claim and desire to secure by Letters Patent—

1. In a lead-pencil, the combination, with the clasping-cylinder and apertured and leaded 75 sheath, of the apertured stop and means to hold the lead in place, substantially as and for the purpose set forth.

2. In a lead-pencil, the combination, with the clasping-cylinder B and the longitudinally- 80 apertured and leaded sheath A, of the apertured disk or stop b and the tube C, substantially as and for the purpose set forth.

In testimony whereof I affix my signature in presence of two witnesses.

BRADLEY ALLAN FISKE.
